UNITED STATES PATENT OFFICE

THOMAS BYRNE, JR., OF CHICAGO, ILLINOIS

CAISSON CONSTRUCTION

Application filed April 6, 1931. Serial No. 528,131.

This invention relates to improvements in caisson construction and, more especially, such construction for making foundations. My invention may be utilized, for example, in the making of piers, foundations, supports, and the like, for buildings, bridges, and other structures. Such supports or foundations frequently must be sunk to great depths in the earth and it is necessary or advisable to first sink a cylindrical caisson to the desired depths. The caisson is then filled with concrete which solidifies to make the permanent support or foundation.

Among the features of my invention is the provision of such caisson construction made of cylindrical sections, thus facilitating handling of the same. Means are also provided for joining the sections together as the same are lowered or sunk into the earth.

Another feature of my invention is the provision of an improved shoe member adapted to be placed at the bottom of the caisson sections. Means are also provided for spacing the sections apart slightly with spacers to leave spaces therebetween adapted to be filled with suitable packing material.

Another feature of my invention is the making of the shoe with an enlarged diameter so that the caisson sections on top thereof will be slightly spaced away from the surrounding earth. In connection with this construction, I provide holes through the walls of the sections through which water, oil or grease may be ejected. This water fills the space surrounding the walls of the sections and thus facilitates their downward movement.

Other features and advantages of my invention will appear more fully as I proceed with my specification.

In those forms of devices embodying the features of my invention shown in the accompanying drawings—

Figure 1 is a vertical sectional view; Fig. 2 is a fragmentary view on an enlarged scale similar to Fig. 1, showing more details; Fig. 3 is a top plan view; Fig. 4 is a sectional view taken as indicated by the line 4 of Fig. 3; Fig. 5 is an enlarged vertical section showing the joint between two retaining rods; Fig.

6 is a top plan view showing a modified form of construction; Fig. 7 is a similar view in side elevation; Fig. 8 is a view partly in side elevation and partly in vertical section showing another modification; Fig. 9 is a similar view in top plan; Fig. 10 is a top plan view of another form; and Figs. 11 and 12 are vertical sectional views showing details of the same.

As shown in the drawings, 10 indicates a cylindrical cutting shoe or shoe member having a cutting edge 11 (pointed in cross-section). The upper part of the cutting shoe is slightly reduced in diameter, as indicated by 12, in order to form the shoulder 13. The cutting shoe is preferably of a diameter large enough to allow a workman, or excavating apparatus, or both, to work inside of the same. In the practice of the invention, the earth 14 is removed from inside of the shoe and as this continues, the shoe moves downwardly. It is to be understood that the shoe member 10 is preferably of rather heavy material, for example, wrought iron.

On top of the shoe member, I provide a plurality of cylindrical caisson sections. These sections are built up on the shoe member 10 as it is lowered. Means are provided for attaching the bottom section to the shoe member and for attaching the sections together.

I shall first describe that form of the invention shown in Figs. 1 to 5, inclusive. As here shown, each of the caisson sections is cylindrical in shape, as indicated by 15. These sections, for example, may be made of concrete. The shoe member 10 is provided on its upper surface with a circular groove or trough 16. Numerals 17, 17 indicate nipples projecting upwardly from the bottom of this trough. The lower edge of each shoe section 15 is preferably somewhat pointed, as indicated by 15^a, to conform in shape to the trough 16. The wall of each of the shoe sections 15 is provided with vertical holes 18 containing tubular sleeve members 18 for the reception of retaining bolts 19. Numerals 20, 20 indicate nuts screwed onto the nipples 17 in the shoe member to receive the lower ends of the bolts 19 for the purpose of hold-

ing the first shoe section 15 in position. The sleeves 18 are somewhat shortened at the lower ends and the bolt holes somewhat enlarged to receive the nuts 20. The upper edge of each shoe section 15 is also provided with a trough 21 similar to the trough 16 in the top of the shoe. Numeral 22 indicates a spacing washer in the trough 21 on the top of each shoe section in order to space the next section above away slightly to provide the cracks or spaces 23 which are filled with suitable packing 24. The spacers 22 may be continuous circular washers or a separate washer may be provided for each bolt.

15 In order to hold the sections together, there is provided a nut 25 on the upper end of each bolt. This holds the section below it down and also provides a socket for holding the lower end of the next bolt 19^a above. In 20 this manner, the respective sections are set together and it is to be noted that as the work progresses and the shoe member 10 descends, new sections 15 may be added at the top of the structure. As has been stated, 25 the vertical hole in each of the sections containing the sleeve 18 is somewhat enlarged at the lower end, as indicated by 26, and the lower end of the sleeve 18 somewhat shortened, to form a space to accommodate the 30 nut 25 as the sections are joined together. This construction is similar to the construction above described for accommodating the nut 20 at the shoe member.

Each of the sections is provided with a 35 radial pipe or pipes 27 through the wall having a check valve or valves 28. The pipe 27 is adapted to receive a water hose 29 so that a stream or jet of water, oil or grease 29' can be forced out through the wall of the 40 section to fill the space 9 formed by the shoulder 13 on the cutting shoe between the outer wall of the caisson sections and the surrounding earth 14'.

In Figures 6 and 7, I have shown a modified form of construction in which each of the caisson sections, instead of being cast of concrete in one piece, is made up of a series of arcuate cast concrete blocks 30 laid in staggered relation. In this form, the shoe 50 31 corresponds to the shoe 10 and the bolts 32 correspond to the bolts 19. It is to be understood that the other details of the form shown in Figs. 6 and 7 are similar to those shown in Figs. 1 to 5, except that cast concrete blocks are used to build up the sections.

In Figures 8 and 9, I have shown another modification, in which the concrete sections are cast in situ. In this form of device, there is employed a cutting shoe 33 similar to the 60 shoe 10. Projecting reinforcing bars 34 are used to connect the lowermost section 35 to the shoe 33, it being understood that the lower ends of some of these bars are suitably anchored in the shoe 33. The upper ends of 65 the bars 34 project above the lowermost sec-

tion 35 in order to tie the next section to be cast to the lower section. When a new section is to be added, the forms 36, 37 are put in place and another section cast in situ. It is to be understood that the lowermost section 35 is similarly cast on the shoe 33 by using forms such as the forms 36, 37.

In Figures 10, 11 and 12, I have shown a different method of fastening the sections together. As here shown, the upper edge of one section 38 is provided with the trough 39, in the bottom of which is placed a circular strip 40 provided with keyhole slots or openings 41. The lower edge of a caisson section 42 next above is provided with depending bolts 43 having heads 44 adapted to be located in the keyhole slots 41 by a slight rotary motion of the upper section, in the usual manner. Two sections 42 and 43 are shown locked together in Fig. 12.

While I have shown and described certain embodiments of my invention, it is to be understood that it is capable of many modifications. Changes, therefore, in the construction and arrangement may be made 90 without departing from the spirit and scope of the invention as disclosed in the appended claim, in which it is my intention to claim all novelty inherent in my invention as broadly as permissible, in view of the prior art.

What I regard as new, and desire to secure by Letters Patent, is:

In caisson construction; a cylindrical cutting shoe with upwardly projecting nipples; 100 nuts adapted to be screwed on said nipples; a plurality of cylindrical caisson sections adapted to be stacked up on said shoe member as the same is lowered; means for attaching the bottom section to the shoe member, said means including bolts extending through the wall of said section adapted to be screwed into said above-mentioned nuts; and means for attaching the sections together, said means including nuts adapted to be screwed on to the upper ends of the above-mentioned bolts, said nuts engaging the upper surfaces of sections, the lower ends of bolts in the walls of sections above adapted to be screwed into said nuts.

In witness whereof, I have hereunto set my hand this 3rd day of April, 1931.
